SPOON OR SIMILAR ARTICLE OF FLATWARE

Arnold Thaler, New York, N. Y.

Application May 10, 1956, Serial No. 41,434

Term of patent 14 years

(Cl. D54—12)

FIG. 1

FIG. 2

FIG. 3

FIG. 4

Fig. 1 is a top plan view of a spoon embodying my new design.

Fig. 2 is an edge view showing the configuration of the spoon as seen from the side.

Fig. 3 is a bottom plan view of a spoon embodying my new design.

The essential features of the design reside in the portions shown in full lines in the drawing.

I claim:

The ornamental design for a spoon or similar article of flatware, as shown and described.
